RUDOLPH L. HANAU, OF BUFFALO, NEW YORK.

METHOD OF MAKING DENTAL RECORDS.

Application filed June 3, 1925. Serial No. 34,718.

My invention relates to methods of preparing and registering records of maxillo-mandibular relation for mounting casts on and adjusting dental articulators.

5 The use of occlusal rims and the making of wax records are not new in the art to which this invention pertains. It has been common practice in making dental records to direct a patient to bite into a body of wax or similar substance formed of layers or arranged in bulk form all along the ridge or in a series of separate bodies, preferably one at each heel of the rim and one in the anterior portion; such wax or similar bodies 15 being ordinarily attached to more resistive bases, thus forming the occlusal rims which serve as dummies or patterns for a future prosthetic denture.

It has also been common practice to interpose layers of wax between occlusal rims, full natural dentures, and partial dentures complemented by partial occlusal rims, when making bite records intended to effect maxillo-mandibular registrations.

25 The action of biting into wax, or similar material, is coincident or attended with the application of muscular forces. The magnitude, direction and point or points of application of these forces is not controllable by the patient, nor the dentist. It is quite apparent that the dentist does not know the magnitude, direction, nor the exact point or points of application of force during the act of biting, and that the patient cannot bite to 35 conform to a specified force.

It is also generally understood that it is difficult, if not entirely impossible, to have the wax chill uniformly so that its resistance to a biting force remains even all along 40 the biting surfaces; and it is furthermore not generally understood, nor considered, that a relative change of position occurs between the dentures, or their equivalents, and consequently between the supporting mandible 45 and maxilla, respectively, on account of pressure applied to full or partial prosthetic restorations resting upon resilient supporting tissues, which pressure is more or less compressing or displacing said tissues. Such change 50 of positional relation leads to a different registration of the mandible with reference to the maxilla with each bite and thereby affects the adjustments made on an articulator.

55 According to my improved method of reg-

istration, all records are made with a definite and controllable closing force, which is absolutely essential to secure definite and repeatable registrations of jaw relations, in contradistinction to the method universally practiced in which a relative change of position of the mandibular and the maxillary dentures and their supporting jaws, and consequently between the mandible and the maxilla occurs 60 upon application of forces varying in magnitude, direction and point or points of application.

For example, under established practice, dentures are mounted in centric relation of the mandible to the maxilla with a record 70 made irrespective of the pressures applied and the dentures accordingly mounted in an articulator. Records are then taken in the protrusive relations irrespective of pressures on the ridges mounted in the recorded relation and the articulator adjusted to the records thus obtained.

The adjustment of the parts of the articulator relied upon to meet the anatomical requirements vary, showing conclusively that 80 the making of records under varying pressures results in a change in the relative positions between the dentures and the supporting mandible or maxilla, and in consequence, in a relative change of position of the mandible to the maxilla. It was believed logical therefore to conclude that any method under which records are taken under pressure is unreliable and impracticable and this has been 85 amply confirmed by extended experiments. 90

The primary object of my invention is to register jaw relations when no forces are brought into action, for the purpose of making prosthetic restorations which are devoid 95 of cusp interference during unstrained function to begin with.

The method of preparing and registering records of maxillo-mandibular relations for mounting casts on and adjusting dental articulators in accordance with my invention 100 is diagrammatically illustrated in the accompanying drawings in which.

Fig. 1 is a schematical illustration of a maxillary denture.

Fig. 2 is a schematical illustration of the 105 mandibular denture.

Fig. 3 is a schematical illustration of a record produced in accordance with my invention.

Figs. 4, 5 and 6 are schematical illustra- 110

tions of a mandible and a maxilla with wax records made in accordance with my invention under different conditions.

Fig. 7 is a schematic view similar to Fig. 6, showing a record taken in accordance with customary practice and illustrating the supporting tissues compressed or displaced at the posterior ends thereof.

Designating the several parts illustrated 10 in the drawings, the numeral 8 designates the maxillary denture having a denture seating surface 9 and masticatory or closing surfaces 10. The mandibular denture is designated by the numeral 11 and has a denture seating surface 12 and masticatory or closing surfaces 13. These dentures may also be referred to as occlusal rims.

The record, illustrated separately in Fig. 3 and between the maxillary and mandibular dentures in Figs. 4, 5, 6 and 7, is designated by the numeral 14 and the record illustrated in Figs. 4, 5 and 6 I term a "rest record" while the record illustrated in Fig. 7 I refer to as a "bite record", the distinction being occasioned by reason of the fact that the rest records are produced with a magnitude of force at zero, or in other words under no pressure, while the bite record is produced under pressure. This record has the upper and lower recording or closing surfaces 15.

16 designates the maxilla, 17 the glenoid fossa at the rear end thereof, 18 the mandible having at its rear end the upstanding condyle head 19 between which and the wall of the 35 glenoid fossa, fibro cartilage 20 is shown. The glenoid fossa, the condyle head, and the fibro cartilage between the two form the condyle centers for the jaw members referred to as maxilla and mandible.

Between the maxilla and the maxillary denture supporting tissues 21 are illustrated, and similar tissues 22 shown between the mandible and the mandibular denture.

Of all magnitudes, directions and points 45 of application of forces which a patient could possibly apply in the act of making a dental record, there is only one magnitude which is definite, and that is the magnitude nil, which may be termed zero, but a magnitude of force at zero has no direction and no point or points of application of force, and consequently according to my method, which has been developed to register all jaw relations with a closing force designated zero, 50 all transmission of muscular forces to the closing or recording surfaces 15 is eliminated and the purpose of using the term "closing force" is to distinguish from the term "biting force" in which magnitude, direction, and point or points of application of forces are 55 applied.

Biting, which implies closing with muscle stress, infers the action of force, and biting into wax or other like material is always attended with an application of more or less 60

force, depending upon the resistance of the wax.

In order to reduce the magnitude of forces to a minimum, the material which is used for registration should be of a soft and even consistency, and the ultimate record itself requires a consistent matrix or impression. Both qualifications are inherent with wax; the first, when the same is heated, and the second when it is cooled or chilled. While it is possible to soften wax to a desired consistency by heating, it is not always attended with an even distribution, nor with an even hardening or setting of the wax. Consequently, when biting into the wax, some parts or fragments of the recording surfaces 15 offer a greater resistance than others, thereby causing an undue compression or displacement of the occlusal rims 8 and 11, or their equivalents and of the tissues below or above 70 and about the more resistive wax portions depending upon the resilient and like effect of the tissues. These parts, fragments, spots or areas, as they may be termed, underneath or above the occlusal rims when 75 pressed against the tissues, become raised after pressure ceases and are detected by visual or digital observations, or both, interpretation by the dentist of the patient's sense of touch, or by measurements when the patient closes into the recording surfaces 15 of the chilled record with no pressure applied. 80

Under my improved method the patient is directed to close slowly into the recording surfaces 15 of the jaw relation registered and 100 at the moment of contact of the recording surfaces, some of their parts may make premature contact, illustrated for example at 23, Fig. 4; 24, Fig. 5; and 25, Fig. 6; and these parts will be found to have been the parts 105 which, on account of local pressure, yielded with the tissues and have become raised or lowered in part by the tissues after pressure ceased, as the case may be.

Specifically setting out my method, the 110 patient is first directed to bite into the prepared softened wax, or other suitable material, in the desired jaw relation, irrespective of the pressure he applies. The wax having the impression therein is then permitted to 115 chill. The patient is next directed to close the jaws carefully and gently until the denture or occlusal rim 8 is felt or observed to come in contact with the record thus far made and supported by the denture 120 or occlusal rim 11, but without applying any pressure to said record. The parts of the record thus far made, not in contact with the denture or occlusal rim 8, are then noted, either by visual or digital observation, or by 125 interpreting the patient's sense of touch, and molten or softened wax is applied to those parts of preferably the upper recording surfaces 15 formed in the wax which are found to be spaced from the denture or rim 8, and 130

consequently have no contact therewith. The record is thus built up and the building up of the spaces is continued until even contact throughout is achieved. This method of building up spaces may be, or is complemented by heating high spots of the record where premature contact was made so as to reduce the same, such high spots being detected in the same manner as the detection made of the 10 low spots or spaces. It may at times be found more expeditious to first reduce the high spots, which may be accomplished by heating and eliminating their bulk by closing movement of the jaws and then complementing this reduction by building up the spaces or low spots in the manner set forth. One or the other of these operations may give the desired record, yet both operations are frequently applied alternately. In addition to a record thus 20 made, a last operation may be resorted to by lightly heating one entire recording surface 15 of the record for a final closing and re-checking of the record.

By the term "rest record" I mean a record 25 made with no jaw pressure applied, and by the term "bite record" I mean a record made solely with pressure applied. The wax may be of a consistency permitting the first impression to be made therein without the exercise of 30 force tending to compress the supporting tissues of the jaws and when the wax is of such consistency, even the first operation may be one exercised under no pressure, i. e. a rest record.

35 Where in the claims, the term "wax" is employed, it is intended to include any composition, or substance possessing, more or less, the qualities of wax, as various dental compositions in addition to wax, are now being used for making dental records.

40 In preparing the wax or other substance for records, it is at times advisable to build up the same in horizontal strata and at other times in vertical strata upon the resistant base; or, the wax or other substance may be 45 employed in bulk form.

Having thus described my invention, what I claim is:

1. The method of producing dental records, which consists in applying wax to dentures or occlusal rims, in then gently closing the dentures or rims to produce impression records upon suitable recording surfaces of 50 said wax without the application of pressure, and in then forming the closing surface of 55 said body of wax so as to contact throughout its entire length with its co-operating and determining element under no pressure.

2. The method of producing dental records, which consists in applying wax to dentures or occlusal rims, in then closing the dentures or rims to form impressions in the 60 wax and allowing the wax to chill, in then gently closing the dentures or rims without 65 pressure until contact at one or more points

is made, and in finally building up the wax at all parts spaced from a denture or rim.

3. The method of producing a dental record, which consists in applying softened wax to a denture or occlusal rim, in forming a 70 recording surface in said wax by closing the jaws without pressure, in then allowing the wax to harden, in then closing the jaws gently without pressure until contact is noted at one or more points between the wax and the denture or rim devoid of wax, in then softening the wax, and in finally reducing the bulk of the wax at the points of contact by closing movements of the jaws. 75

4. The method of making a dental record, which consists in biting into a body of softened wax to form impressions therein and allowing the wax to chill, in then closing the jaws slowly without pressure until contact is noted between the wax and the denture devoid of wax, in reducing the bulk of the wax at the points of contact noted until under slow closing movement of the jaws without pressure all parts of the wax come in contact with the denture devoid of wax without 80 muscle stress transmitted at the closing or recording surfaces or compression or displacement of tissues of the jaws. 85

5. The method of making dental records, which consists in making a wax impression 90 of the denture on the closing surfaces of the dentures, in reducing the bulk of the wax along parts thereof and building up the remaining parts thereof until the recording 95 surfaces contact at all points without the use of pressure. 100

6. The method of making dental records, which consists in making a wax impression of the denture, in determining points of contact upon closing movement under no pressure, and in reducing the bulk of the wax impression along parts thereof until even closing contact under no pressure is made along 105 the entire wax recording surface.

7. The method of making dental records, which consists in making wax impression records of the closing surfaces of a denture, and in building up the wax impression at 110 parts thereof until contact along the entire recording surface so formed is had under no pressure. 115

8. The method of making dental records, which consists in making a wax impression of the dentures, in then heating the wax at the high points, in then reducing the bulk 120 of the wax along the heated parts by closing movement of the jaws and building up the remaining parts of the wax impression with molten wax, and in continuing both the reducing and building up steps alternately until all parts of the record thus made are of even contact throughout their closing surfaces when under no pressure. 125

9. The method of making dental records, which consists in making a denture impres- 130

sion in heated wax, in allowing the wax with the impression therein to cool, in then closing the dentures slowly to note points of contact of the denture devoid of wax with the wax record thus far made, in then applying soft wax to the parts of the wax record out of contact with said denture until contact of said denture is made along the entire recording surface of said record, and in lightly heating one of the entire surfaces of the record thus made and slowly closing the jaws against said impression until contact under no pressure is made along the entire recording surface or surfaces, respectively, of said record.

10 15 10. The method of making a dental record, which consists in biting into a body of softened wax to form impressions therein and allowing the wax to chill, in then closing the jaws slowly without pressure until contact is noted between the wax and the denture de-

void of wax, and in then building up the wax over the remaining portions thereof until under slow closing movement of the jaws without pressure all parts of the wax come in contact with the denture devoid of wax without muscle stress transmitted at the closing or recording surfaces, or compression or displacement of the tissues of the jaws.

20 25 11. The method of registering jaw relations, which consists in applying wax to a denture or occlusal rim, in then biting into the wax to form impressions in the closing surface thereof, and in then forming the closing surface of said body of wax so as to contact throughout its entire length with its co-operating and determining element under no pressure.

30 35 In testimony whereof I affix my signature.

RUDOLPH L. HANAU.
